UNITED STATES PATENT OFFICE

156,944

VEGETABLE CUTTER OR SIMILAR ARTICLE

Ralph P. De Vault, Arcadia, Calif.

Application November 23, 1948, Serial No. 149,781

Term of patent 14 years

(Cl. D89—1)

To all whom it may concern:

Be it known that I, Ralph P. De Vault, a citizen of the United States, residing at Arcadia, in the county of Los Angeles and State of California, have invented a new, original, and ornamental Design for a Vegetable Cutter or Similar Article, of which the following is a specification, reference being had to the accompanying drawing, forming part thereof.

Figure 1 is a view in perspective of a vegetable cutter or similar article embodying my new design;

I claim:

The ornamental design for a vegetable cutter or similar article, substantially as shown.

RALPH P. DE VAULT.
